UNITED STATES PATENT OFFICE.

JESSE FERNANDO WALDEN, OF MERRYVILLE, LOUISIANA.

AEROPLANE.

1,277,277.

Specification of Letters Patent. Patented Aug. 27, 1918.

Application filed December 5, 1917. Serial No. 205,548.

To all whom it may concern:

Be it known that I, JESSE FERNANDO WALDEN, a citizen of the United States, residing at Merryville, in the parish of Beau- 5 regard, State of Louisiana, have invented a new and useful Aeroplane; and I do hereby declare the following to be a full, clear, and exact description of the invention, such as will enable others skilled in the art to which

10 it appertains to make and use the same.

This invention relates to an improved aeroplane, and one of the objects of the invention is to provide an aeroplane having a gas bag provided with a compartment sus- 15 pended therefrom in combination with a compressed air tank whereby air may be injected into said compartment for breathing purposes.

A further object of the invention is the 20 provision of a motor operated pump forcing air into said tank.

A further object of the invention is the provision of a compartment at the rear of the aeroplane for an operator, whereby a 25 motor for operating a propeller may be controlled.

A further object of the invention is the provision of improved lateral steering and elevating planes, whereby the dirigible aero- 30 plane may be controlled.

A further object of the invention is the provision of improved means for operating the lateral steering and elevating planes.

A further object of the invention is the 35 provision of an aeroplane having a gas bag which is provided with forward and rear planes, which are in the form of laterally extending fins having braces to hold them rigidly in place.

40 In practical fields the details of construction may necessitate alterations falling within the scope of what is claimed.

The invention comprises further features and combination of parts as hereinafter set 45 forth, shown in the drawings and claimed.

In the drawings:

Figure 1 is a view in side elevation of the improved dirigible aeroplane constructed in accordance with the invention.

50 Fig. 2 is a plan view of the same.

Fig. 3 is a longitudinal sectional view on line 3—3 of Fig. 2.

Fig. 4 is a rear view of the aeroplane.

Fig. 5 is a cross sectional view on line 5—5 55 of Fig. 1.

Fig. 6 is a longitudinal sectional view on line 6—6 of Fig. 1.

Fig. 7 is a detail perspective view of the lateral oscillating and vertical oscillating lateral steering and elevating plane. 60

Fig. 8 is a sectional view through the mounting of the lateral oscillating plane.

Fig. 9 is a detail sectional view through the mounting of the elevating plane.

Referring more especially to the drawings 65

1 designates the gas bag of the aeroplane, which may be any suitable shape, preferably elongated and tapered at both ends, substantially cigar shaped and comprises the usual skeleton frame 2 which consists 70 of the longitudinal stays 3 and the annular bands 4, and the outer skin or covering 5. Carried by the top of the outer skin in any suitable manner as shown at 6 and extending horizontally and laterally of the gas bag 75 are forward and rear planes 7 and 8, which, in plan view are substantially V-shaped. Extending laterally from the sides of the outer skin of the gas bag are forward and rear side planes 9 10, which, in plan view 80 are also substantially V-shaped. The planes 7 and 9 and 8 and 10 are reinforced relative to each other by the braces 11 and 12. The forward side planes 9 are braced relative to an air tank 13 (which is suspended from the 85 forward portion of the bottom of the gas bag by the members 14, which have arms 15 secured to the gas bag) by means of the braces 16. The rear side planes are reinforced relative to the side walls of a compartment 17 (which is suspended from the rear portion of the bottom of the gas bag, by means of the members 18) by the braces 19. These planes 7 and 9, and 8 and 10, act 90 as fins, which operate to prevent rolling or turning of the aeroplane. Upper and lower decks or platforms 20 and 21, are carried by the forward part of the gas bag, and a frame 22 supports the forward end of the upper deck or platform. A suitable gaso- 95 lene tank 23 is supported between the forward end of the gas bag and the frame 22. A motor 24 preferably operated by gasolene is carried by the deck or platform 21, and 100 receives its supply of gasolene from the tank 23 through the pipe or tube 25. This motor 24 operates a conventional form of pump 26, whereby air under pressure is forced into the tank 13. The compartment 17 may be 105 any suitable shape preferably rectangular, 110

and a pipe 27 extends from the air tank 13 into the compartment, and is provided with an air gage 28. A second pipe 29 also extends from the air tank 13 through the forward wall of the compartment, and is provided with a valve 30, whereby air under pressure may be controlled into the compartment. A suitable or conventional form of gasoline motor 31 is carried by the upper deck or platform 20, and has its shaft 32 mounted in a bearing of the frame 22 and is provided on its end with a conventional form of propeller 33. The other end of the shaft has the usual fly wheel 34, and the motor 31 may receive its supply of gasoline from the tank 23 by means of the tube or pipe 35. To the rear of the motor 31 and on the deck 20, a suitable compartment 36 is provided, in which an operator for handling the motor 31 may be employed. The compartment 17 has its sides provided with port holes 37 having transparent closures 38 preferably of glass, and projecting laterally from the compartment 17 is an extension 39. This extension has a rail 40, whereby a person may stand on the extension direct and observe the course of the aeroplane. A suitable door 41 in one of the sides of the compartment 17 allows an attendant or observer to pass from the compartment out on the extension and vice versa. The rear part or wall of the compartment 17 has an opening 42 to allow the compressed air to escape. Extending downwardly and rearwardly from the rear part of the compartment 17 is a pair of arms 43, which are connected by a transverse bar 44, which has its ends provided with downwardly extending ears 45. A shaft 46 disposed perpendicular has its upper end mounted in a bearing of the gas bag as shown at 47, and its lower end in a bearing 48 of the cross bar 44. A laterally oscillating plane 49 has its arms 50 mounted on the shaft 46, there being collars 51 secured by the pins 52 on the shaft 46 to prevent axial movement of the plane 49. A bevel gear 53 is integral with the lower arm of said plane 49, and with which a bevel gear 54 carried by the shaft 55 meshes. This shaft 55 is mounted in a bearing 56 on the interior of the compartment 17 and in a bearing 57 of the rear end wall of said compartment. The forward end of the shaft 55 has a bevel gear 58. A suitable base plate 59 is mounted upon the floor of said compartment 17 and has a bearing 60 for the shaft 61 which has a bevel gear 62 to mesh with the bevel gear 58, whereby upon turning the shaft 61

in one direction or the other by grasping its hand wheel 63, it is to be noted that the plane 49 may be oscillated laterally; whereby the aeroplane may be guided in one direction or the other, laterally or held straight ahead. Mounted in bearings of the ears 45 is a shaft 64, fast to which is an elevating plane 65. An arm 66 has its hub 67 secured by a pin 68 on one end of said shaft 64. A link 69 has one end pivoted to the arm 66 as shown at 70. The base plate 59 is provided with a segment quadrant 71, to which a lever at 72 is pivoted. The lower end of this lever 73 is pivoted at 74 to the forward end of the link 69, so that by oscillating said lever 73 the elevating plane 65 may be manipulated to direct the aeroplane to move upwardly or downwardly. A suitable dog 75 actuated by the conventional form of hand grip 76, is designed to engage any one of the teeth of the segment quadrant for holding the lever 73 in different adjusted positions. Consequently it will be observed that by manipulating the planes 49 and 65, the aeroplane may be controlled in its course. A suitable binnacle 77 adapted to have a compass (not shown) is arranged in the compartment 17 adjacent the controlling means of the planes 49 and 65.

The invention having been set forth what is claimed as new and useful is:—

In a dirigible air ship, a gas bag, a compartment suspended therefrom, propelling means for the air ship, a pair of arms projecting downwardly and rearwardly from the rear ends of the compartment, a bar connecting said arms, laterally oscillating means mounted in bearings of the bar and gas bag for steering the air ship in its lateral course, the ends of said bar terminating in downwardly extending ears, a transverse shaft mounted in bearings of said ears and provided with a plane to be oscillated vertically for elevating or lowering the air ship, said elevating plane being below the laterally moving means, one end of said transverse shaft having an arm extending downwardly therefrom, and means having a link connection with said last named arm for operating the elevating plane.

In testimony whereof I have signed my name to this specification in the presence of two subscribing witnesses.

JESSE FERNANDO WALDEN.
